UNITED STATES PATENT OFFICE.

WALTER A. GENESY, OF SAN FRANCISCO, CALIFORNIA.

DESIGN FOR A CHILD'S ROMPER.

36,354.

Specification for Design. Patented Oct. 5, 1920.

Application filed April 26, 1920. Serial No. 376,894. Term of patent 3½ years.

To all whom it may concern:

Be it known that I, WALTER A. GENESY, a citizen of the United States, residing at the city and county of San Francisco, State of California, have invented a new, original, and ornamental Design for Children's Rompers, of which the following is a specification, reference being had to the accompanying drawing, forming part thereof.

The illustration is a plan view of a child's romper showing my new design.

What I claim and desire to secure by Letters Patent is:—

The ornamental design for a child's romper, as shown.

WALTER A. GENESY.
